UNITED STATES PATENT OFFICE.

HARRY A. ATWOOD, OF MILWAUKEE, WISCONSIN.

CHAIR.

Application filed November 18, 1920. Serial No. 424,877.

To all whom it may concern:

Be it known that I, HARRY A. Atwood, a citizen of the United States, and resident of Milwaukee, in the county of Milwaukee and State of Wisconsin, have invented new and useful Improvements in Chairs, of which the following is a description, reference being had to the accompanying drawings, which are a part of this specification.

10 This invention relates to certain new and useful improvements in chairs, and refers more particularly to features of novelty and advantages in swivel chairs with tiltable seats.

15 Heretofore, in chairs of this type, the chair irons, including the head and spider, have been cast, which, while performing the desired functions in a satisfactory manner, are objectionable due to their great weight.

20 Hence, it is one of the objects of this invention to provide a chair iron construction whereby all the parts thereof may be struck or stamped from bendable metal to produce a structure which will be of the required strength and, at the same time, extremely light in weight.

Another object of this invention is to provide a chair of the type described in which a spider includes a central or main portion having down struck spaced lugs or arms and having chair seat engaging arms rigidly secured thereto by the improved means hereinafter described.

25 A further object of this invention is to provide an improved spring cushion including a U-shape member upon the arms of which are mounted two opposed cap members having cushion springs confined therebetween.

30 A still further object of this invention resides in the means for securing the cushion springs in position. Beside the accomplishment of the above and other purposes, other salient features of the invention are simplicity of construction, economy in manufacture, accessibility of adjusting parts, and a structure of pleasing appearance.

With the above and other objects in view which will appear as the description proceeds, my invention resides in the novel construction, combination and arrangement of parts substantially as hereinafter described and more particularly defined by

the appended claims, it being understood that such changes in the precise embodiment of the herein disclosed invention may be made as come within the scope of the claims.

55 In the accompanying drawing, I have illustrated one complete example of the physical embodiment of my invention constructed according to the best mode I have so far devised for the practical application of the principles thereof, and in which:

60 Figure 1 is a view looking at the side of a portion of a chair equipped with my invention, parts of the chair iron being broken away and in section to more clearly illustrate details of construction;

65 Figure 2 is a view part in section and part in elevation taken on the line 2—2 of Figure 1;

70 Figure 3 is a fragmentary top plan view of the chair iron, the outer portions of the chair seat engaging arms being broken away;

75 Figure 4 is a view part in section and part in elevation taken on the line 4—4 of Figure 1;

80 Figure 5 is a perspective view of the securing member for firmly engaging all of the seat supporting arms at their inner ends to firmly secure the same in the spider; and

85 Figure 6 is a perspective view of the pair of seat engaging arms that are connected together by an intermediate portion.

Referring now more particularly to the accompanying drawings, it will be perceived that the improved chair comprises an adjustably threaded vertical post or shaft 10, 90 which is engageable with a suitable supporting base, not shown, a spider or seat supporting frame 11 having outwardly extending arms 15, 16, 17 and 18 carried thereby in the novel manner to be hereinafter described, and secured at their outer ends to the under face of a seat bottom 19, and a lower supporting member or head 20 secured on the top of the post 10, in the manner hereinafter described, and having a 100 pivotal connection with the spider or seat supporting frame 11.

The head 20 has one end formed in the shape of an inverted cup, as at 21, in which a second cup member 22 has a snug fit, the 105 end walls of the cups 21 and 22 being cen-

trally bored to receive the upper reduced end 23 of the shaft 10. The end wall of cup 22 abuts the shoulder 24 formed at the inner end of the reduced portion 23 of the shaft 10, and the extreme upper end of the shaft 10 projects slightly beyond the end wall of the cup 21 and is then riveted or bored, as at 25, to firmly confine said cup end walls between the shoulder 24 and the head formed by the boring 25. This construction strengthens the head where the shaft is connected therewith and thus permits the formation of said head by stamping.

The head 20 has its portion extending from the hub provided by the cups 21 and 22 formed on the upwardly projecting side flanges 26 for strength and the extreme outer end thereof is projected upwardly, as at 27, to provide means for limiting the forward tilting of the chair seat and for receiving one end of the tension bolt of the cushion spring as hereinafter provided. The flanges 26 are provided, juxtapose the hub of the head, with two alined upstanding projections or ears 28 that are axially bored, as at 29, to receive a hinge pintle 30, the outer ends of which are engaged in alined apertures in the lower ends of a pair of depending spaced lugs 31 struck from the spider or chair seat supporting frame 11.

The spider 11 is stamped from bendable material and is formed with two pairs of oppositely extending arms 32 and 33, the arms 33 being longer than the arms 32 and having their outer ends struck downwardly from a point spaced from the center of the spider to form the lugs 31. The arms of the spider are provided with upstanding flanges at the sides thereof to reinforce the same and to provide channels in the top face thereof in which the inner ends of the chair seat engaging arms are positioned. The chair seat engaging arms 16 and 18 are formed in one piece and connected at their inner ends by a strip 34 of a width equal to the distance between the upstanding side flanges 35 of each chair seat supporting arm. As depicted in Figures 1, 2, and 3, the connected together arms 16 and 18 are positioned in the channels of the alined extension 33 and the arms 15 and 17 positioned in the channels of the alined extension 32 with their extreme inner ends abutting the adjacent sides of the connected together arms 16 and 18.

The connecting portion 34 of the arms 16 and 18 is apertured, as at 36, to receive a rivet or other securing member 37 which passes through a central aperture in the spider 11 and through a cross shaped locking or securing member 38 having diverging lugs 39 which engage the chair seat engaging arms adjacent their inner ends. The extreme outer ends of the lugs 39 are struck

inwardly, as at 40, so that when the fastening member 37 is drawn tight, the portions 40 will be at all times under tension against the inner ends of the chair seat engaging arms. The chair seat engaging arms may be, if desired, further secured in place by rivets 41, or the like, which pass through said arms and the projections 32 and 33 of the spider. The flanges of the extensions 32 and 33 are provided with projections 42 near their outer ends, which are bent over as depicted in Figures 1, 2, and 3, after the chair seat engaging arms are in place to further secure the same to the spider as will be readily apparent.

By reason of the hinge pintle 30 engaging the lugs 31, the spider 11 is in pivotal connection with the head, and said pivotal connection is limited in one direction by the upstanding part 27 of the head and is yieldably resisted in the opposite direction by the improved spring cushion now about to be described. Also secured in place by the fastening rivet 37 and the rivets 41 of the arms 16 and 18, is a plate member 43 which extends across the space between the lugs 31 and has its lower end provided with laterally extending parts 44 which engage against the rear sides of said lugs. Formed in the plate member 43 are two horizontally alined apertures 45, through which are passed the arms 46 of a U-shape clip, the closed end 47 of which engages against the plate member 43. The arms 46, of the U-clip are retained in substantially central position with respect to the openings 25 by a lip 48 struck from the plate member 43 and engaging the closed end 47 thereof, as depicted in Figures 1 and 4, and mounted on the arms 46 are two opposed elongated cap members 49 and 50, the outer cap member 49 being secured in place by nuts 51 in threaded connection with the ends of the arms 46.

Coiled about each arm 26 and confined between the cap members 49 and 50 are two extensible springs 52, which at all times seek to urge said cap members apart, and passed through centrally alined openings in said cap members is a tension adjusting bolt 53 having a head on its inner end abutting the outer face of the cap member 50 and its outer threaded end passed through an opening 54 in the part 27 of the head and having an adjusting nut 55 mounted thereon. A washer 56, having a pointed inner face engaged in an indented part 57, is interposed between the nut 55 and the head portion 27, as depicted in Figure 1. From this construction, it will be readily seen that upon the rearward tilting of the seat 19, the springs 52 will be compressed, and that by reason of this construction an efficient and durable spring cushion is obtained. The cap 49 is recessed adjacent each nut 51 to prevent the accidental unscrewing thereof, and

the tension bolt 53 is secured at its point of entry through the cap 50 so that a rotation of the nut 55 will not rotate the bolt and hinder the adjustment of the spring tension.

5. What I claim as my invention is:

1. In a device of the class described the combination of a spider of bendable metal having a plurality of laterally extending channeled members all in the same horizontal plane, the flanges of said channeled members being provided with overturned projections; a seat supporting arm secured within the channel of each of said members and engaged by said overturned projections; means comprising a stamped metal head for connecting said spider to said support; and means carried by said head adapted to be engaged by one of said arms to limit the movement of said seat in one direction.

2. In a device of the class described, a spider having a plurality of laterally extending channeled projections, seat engaging arms having their inner ends disposed within the channels of said projections, a securing plate having lugs extending into the channel of each projection to engage the arm positioned therein, and means connecting the spider with a support.

3. In a device of the class described, a spider having a plurality of laterally extending channeled projections, seat engaging arms having their inner ends disposed within the channels of said projections, a securing plate having lugs extending into the channel of each projection to engage the inner ends of said arms and secure said arms in the channels, securing means positioned adjacent the outer ends of the projections for engagement with said arms, and means connecting the spider with a support.

4. In a device of the class described the combination of a spider stamped from a single piece of bendable metal having a pair of spaced depending lugs and a plurality of radially extending channeled members all in the same horizontal plane; a seat supporting arm rigidly secured within the channel of each of said members; a head member provided with an integral extension adapted to be engaged by one of said arms to limit the movement of said seat in one direction; means for pivotally connecting said depending lugs to said head member; and resilient connections between said spider and head member adapted to yieldingly resist movement of said spider about its pivot.

5. In a device of the class described the combination with a support of a spider member; a plurality of seat supporting arms rigid with said spider member; a head member of stamped bendable material provided with a cupped portion adapted to engage said support; and a cup-shaped

member carried by said support adapted to fit within said cupped portion of said head to form a pivotal bearing therefor.

6. In a device of the class described, a spider, a head, a pivotal connection between the spider and head, a transversely extending part carried by the spider and provided with two spaced openings therein, an upstanding part carried by the head and having an opening positioned substantially centrally with respect to the openings in said transversely extending part, a U-shaped member having the ends thereof projected through the openings in said transversely extending part, opposed elongated cap members mounted on the arms of said U-shaped member, an extensible spring coiled about each arm of said U-shaped member and confined between the cap members, and a tension bolt connected with the innermost cap member and the head.

7. In a device of the class described, a spider, a head, a pivotal connection between the spider and head, a transversely extending part carried by the spider and provided with two spaced openings therein, an upstanding part carried by the head and having an opening positioned substantially centrally with respect to the openings in said transversely extending part, a U-shaped member having the ends thereof projected through the openings in said transversely extending part, means retaining the arms of said U-shaped member substantially centrally of the openings.

8. In a chair iron, a spider having two pairs of oppositely extending channeled projections, a chair seat engaging arm within the channel of each projection, and means engaging the inner ends of said arms to secure the same in position and including a cross shaped member positioned at the center of the spider and having securing means for clamping the ends thereof against said arms.

9. In a chair iron, a spider having two pairs of oppositely extending channeled projections, a chair seat engaging arm within the channel of each projection, means engaging the inner ends of said arms to secure the same in position, and a lip on each projection and adapted to be struck over to engage the adjacent arm.

10. In a device of the class described, a head; a spider pivotally secured to said head and having two positions of rest; a pair of coiled springs interposed between said head and spider, normally urging the latter toward one of its positions of rest; a U-shaped member carried by said spider, with its legs passing through said springs; and a cap carried by the ends of the legs of said U-shaped member, engaging one end of said springs, for compressing the latter as

said spider moves toward its other position of rest.

11. In a device of the class described, a head; a spider pivotally secured to said head and having two positions of rest; a U-shaped member non-rigidly carried by said spider; a tensioning bolt non-rigidly carried by said head and extending between the legs of said U-shaped member; caps carried by said bolt

and said U-shaped member; and a pair of coiled compression springs interposed between said caps, and surrounding the legs of said U-shaped member, normally urging said spider toward one of its positions of rest, and resisting movement thereof toward the other position of rest. ¹⁰ ¹⁵

In testimony whereof, I affix my signature.
HARRY A. ATWOOD.
